(57) **CLAIM**

The ornamental design for a signal relay device, as shown and described.

DESCRIPTION

FIG. 1 is a perspective view of the front, right, and top sides of a signal relay device showing our new design;
FIG. 2 is a perspective view of the front, left, and bottom sides of a signal relay device showing our new design;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom view thereof; and,
FIG. 9 is a reference view showing a connected state.
The broken lines shown represent unclaimed subject matter of the signal relay device and form no part of the claimed design.
